UNITED STATES PATENT OFFICE.

GEORGE E. MEEKER, OF MERIDEN, CONNECTICUT.

ADJUSTABLE PITMAN.

SPECIFICATION forming part of Letters Patent No. 453,599, dated June 2, 1891.

Application filed December 30, 1890. Serial No. 376,232. (No model.)

To all whom it may concern:

Be it known that I, GEORGE E. MEEKER, a citizen of the United States, and a resident of Meriden, in the county of New Haven and State of Connecticut, have invented new and useful Improvements in Adjustable Pitmen; and I do hereby declare the following to be a full, clear, and exact description of said invention, reference being had to the accompanying drawings, and to the letters of reference marked thereon, which form a part of this specification.

My invention relates to improvements in adjustable pitmen, and has for its object the production of a strong, simple, durable, and readily-adjustable device for altering the distance between a crank or eccentric and that part of a machine which is to have a reciprocating motion imparted to it; and my said invention is particularly adapted for use in converting the rotary motion of the crank or wrist pin into reciprocating motion of the punch or die in a power-press. In this class of machines, as is well known, the punch or die becomes gradually worn, and to compensate therefor the pitman should have means whereby its length may be increased in order that the limits of motion of the die-carrier will be in a lower plane. The limits of motion, or, in other words, the amount of motion or throw of the die-carrier, should always be uniform, as if otherwise an increase of motion results in a decrease of power. Various devices for obtaining the desired adjustment without alteration of the amount of stroke have been produced, but all, so far as I am aware, are either complicated and expensive or are weak and subject to wear and breakage at the location of the adjusting mechanism. In my device all of these objections are, I believe, obviated.

In the drawings which accompany and form part of this specification, Figure 1 is a front elevation of my improved pitman; and Fig. 2 is a section of the upper part thereof on the line 2 2 of Fig. 1.

A indicates the body of the pitman, having its lower end B shaped so as to be connected in any ordinary manner to the slide or die-carrier (not shown) of a power-press, or to any other part of a machine that is to be reciprocated. At the other end the pitman is

enlarged and provided with an inclined slot or opening C, the upper and lower sides of which form parallel ways for the traveling slide-block D. The angle of inclination of this slot or the ways with respect to a line drawn through the longitudinal center of the body of the pitman should be such that the difference in distance from the lower end B to the opening D' in the block when at one end of the ways, and when at the other end of the ways will equal the length of adjustment that is desired for the pitman—for instance, in a die-press in which an adjustment of an inch and a quarter is desired, the upper end of the ways should be one and one-fourth inch farther from end B than that portion of the ways where the side of the slide-block nearest that upper end rests when the block is at its lower limit. Supposing that in Fig. 1 of the drawings the actual play allowed to the block is four inches and the rise or "grade" of the ways is an inch and a quarter in four inches, then the distance from D' to B, when the parts are in the position indicated in full lines, will be one and a quarter inch less than said distance when the parts are in the position indicated by the dotted lines. It is therefore obvious that by increasing the pitch or incline of the ways this amount of adjustment can be obtained with a shorter length of slot or ways for the block, or the pitch can be less and the ways longer. For a greater or less amount of capable adjustment in the length of the pitman the length of the ways or the incline or pitch thereof may be determined for the purposes desired.

The opening D' is for the wrist-pin or eccentric on the operating-shaft of the machine in which the pitman is employed, and fitted to a screw-threaded opening d in the block is a screw d', having its ends fitted to the ends of the slot so as to turn freely therein, but have no longitudinal movement. To either end of the screw a wrench may be applied for turning it and causing the block to travel on the ways. The said block is preferably formed of two parts d² d³, having flanges d⁴ fitting over the sides of the ways and provided with screws or bolts d⁵ uniting the two parts, which bolts may be tightened for firmly securing the block in any adjusted position by clamping the flanges on the ways.

A scale marked on one of the ways, as at *c*, may be utilized for indicating fine adjustments.

The operation and the advantages of this form of adjustable pitman will be obvious. All of the pressure will be upon parts thoroughly capable of standing it, and by applying the pitman so that the direction of rotation of the wrist-pin will be as indicated by the arrow in Fig. 1 the pressure, when the power utilized is greatest, will be applied approximately at a right angle to the ways, and thus avoid any strain whatever upon the screw.

While I believe the form as illustrated in the drawings to be the most suitable for the pitman of a die-press, it will be understood that modifications may be made without departing from the spirit of my invention. For instance, the upper guideway, instead of being formed integrally with the body of the pitman, may be a rod connected to lugs at each end; and a reversal of the pitman—that is, a connection of the end *B* with the crank or wrist pin of the machine and of the slide-block with the die-carrier—might be found practical in some cases.

Having now described my invention, what I

claim, and desire to secure by Letters Patent, is—

1. A pitman having inclined parallel ways at one end and a slide-block adjustable along said ways, said block and the other end of the pitman being adapted for connection with the wrist-pin and die-carrier of a die-press, substantially as described. 30

2. A pitman having inclined parallel ways at one end and a block fitted thereto, and means for adjusting and holding the block on said ways, substantially as described. 35

3. In a pitman, the combination, with the body thereof having an inclined slot at one end, the sides of the slot being parallel, of a slide-block fitted to the sides of said slot and having means for connection with an eccentric or wrist-pin, a screw for moving the block along the ways, and means for securing the block in any adjusted position, substantially as described. 40

In testimony whereof I affix my signature in presence of two subscribing witnesses.

GEORGE E. MEEKER.
